Patented June 23, 1925.

UNITED STATES PATENT OFFICE.

HERBERT KEMP SMITH, OF NEW ORLEANS, LOUISIANA, ASSIGNOR TO MERLE POWE SMITH, OF NEW ORLEANS, LOUISIANA.

WRIST-WATCH BAND.

Application filed September 26, 1922. Serial No. 590,666.

To all whom it may concern:

Be it known that I, HERBERT K. SMITH, a citizen of the United States and a resident of New Orleans, in the parish of Orleans and State of Louisiana, have invented certain new and useful Improvements in Wrist-Watch Bands, of which the following is a specification.

This invention relates to metal bands for attaching any kind of wrist watch in position on the arm of a person. Heretofore it has been proposed to employ silk ribbon bands or leather bands for attaching watches to the wrist of a person but due to the fact that both the leather, which is usually made of pigskin, and the silk absorb perspiration these bands are very impractical for the purpose. It is an object of this invention to employ a metal band to replace the usual silk ribbon or leather band which will not only be ornamental but which will maintain the watch in position on a wrist without danger of loss of the watch.

It is a further object of the invention to provide a readily releasable catch on the metal band whereby the band may be easily applied or removed when desired, with adjustable means whereby the band may be made to fit wrists of different sizes.

Other objects and objects relating to details of construction will hereinafter appear.

The invention is illustrated by way of example in the accompanying drawings, in which,

Figure 1 is a view in perspective of the wrist watch and band applied to the wrist of a person.

Figure 2 is an end view of the same.

Figure 3 is a view in perspective of the several parts of the band in detached position.

Figure 4 is a transverse section taken on the line 4—4 of Figure 3.

Referring to the drawings, 1 designates a wrist watch having the swivelled eyes 2 and 3 located at opposite ends and adapted to receive the ends of the two sections 4 and 5 of the band. The eyes 2 and 3 are made somewhat elongated in order to respectively receive the rolled or cylindrical ends 6 of the members 4 and 5 of said band.

Each of the members 4 and 5 are curved to conform to the circumference of the wrist of a person. The free end 7 of the member 4 of the band is provided with a plurality of

spaced perforations 8 adapted to receive the slotted lug 9 on the free end 10 of the member 5. As shown more particularly in Figures 3 and 4, the lug 9 is split as at 11 in alinement with a longitudinal slot 12 in the free end 10 of the member 5. Furthermore the lug 11 is in the shape of a frustum of a cone with the larger end rounded and projecting outwardly from the end 10 of the member 5 of the band. The slotting of the end of the member 5 and the lug 9 permits the two sections of the lug 9 to be moved toward each other in order that said lug will readily slip within one of the perforations 8 of the member 4 of the band. After the lug has been inserted through one of said perforations the section of the lug will be expanded by reason of the resilience of the metal of the end 10 of the member 5 and aid in locking the two ends of the members 4 and 5 together.

Slidably mounted on the member 5 of the band is a keeper 13. Said keeper comprises a substantially rectangular portion having an opening therein adapted to be received by both the free ends of the two members 4 and 5 and slidable thereon. Projecting from the upper face of the keeper 13 is a lip 14 provided with a perforation 15 and a finger piece 16. When the lug 9 is inserted within a perforation 8 and projected above the outer surface of the free end 7 of the member 4 the perforation 15 in the lip 14 is adapted to receive the split lug 9 and aid in preventing the lug from becoming disengaged with the perforation 8 in the end 7 of the member 4. The finger piece 16 is bent upwardly from the end of the tongue 14 in order to aid in releasing the tongue 14 from its engagement through the perforation 15 with the split lug 9.

Projecting forwardly from the bottom face of the rectangular member is a second lip 17 spaced from the lip 14 and adapted to engage the under side of the free end 7 of the member 4. This lip cooperating with the lip 14 further aids in maintaining the keeper 13 in position when the split lug 9 is engaged with a perforation 8 in the member 4 and the perforation 15 in the tongue 14.

A plurality of spaced perforations 8 provide for an adjustment whereby the bands may be applied and properly fit wrists of various sizes.

Each of the members 4 and 5 are swing-

able outwardly or toward each other by reason of their pivoted connection through the cylindrical portions 6 on the inner ends of the members 4 and 5 and the eyes 2 and 3 on the wrist watch.

The two members 4 and 5 of the band may be made of any kind of precious metal and may be suitably engraved or decorated to correspond with the decorations or engraving on any style or kind of watch employed in connection with the band.

What I claim is:

1. A band for securing wrist watches to the arm of a person comprising two semi-circular metal members adapted to be pivotally connected to opposite ends of a watch, the free end of one of the members being provided with a plurality of spaced perforations, the free end of the other member being provided with an upstanding split lug in the shape of the frustum of a cone adapted to engage one of the perforations in the free end of the first-mentioned member, a portion of the free end of the second member being split in alignment with the space between the two portions of the split lug whereby the two portions of the lug may be pressed toward each other and be permitted to expand by reason of the resilience of the free end of the second-mentioned member, a keeper slidably mounted on the second member, a lip projecting forwardly from the keeper and provided with a perforation adapted to receive the split lug on the end of the second-mentioned member, a tongue projecting forwardly from the lower face of the keeper and adapted to engage the under side of the free end of the first member when said keeper is locked on the lug of the second member and when the free ends of said members are located in face to face engagement with the split lug received in one of the plurality of perforations in the free end of the first member.
2. A band for securing wrist watches in position comprising a pair of members adapted to be pivotally connected to a wrist watch at their inner ends, the free end of one of the members being provided with a plurality of spaced perforations, a split lug mounted on the free end of the other member, the free end of the said second member being provided with a slotted portion in alignment with the space between the split portions of said lug whereby the split portions of the lug will be located in expanded relation with each other, said split portions of the lug adapted to be contracted and forced through one of the perforations in the free end of the first member with the split portions of the lug expanding within the perforations and locking the free ends of the two members together, and means slidable on the second member and engageable with the split lug for aiding in main-

taining said lug in a perforation in the first member.

3. A band for securing wrist watches in position comprising a pair of members adapted to be pivotally connected to a wrist watch at their inner ends, the free end of one of the members being provided with a plurality of spaced perforations, a split lug mounted on the free end of the other member, the free end of the said second member being provided with a slotted portion in alignment with the space between the split portion of said lug whereby the split portions of the lug will be located in expanded relation with each other, said split portions of the lug adapted to be contracted and forced through one of the perforations in the free end of the first member with the split portions of the lug expanding within the perforations and locking the free ends of the two members together, and a keeper slidably mounted on the second member and provided with a perforation adapted to receive the split lug for aiding and maintaining the lug in position in one of the perforations in the free end of the first member.

4. A band for securing wrist watches in position comprising a pair of members adapted to be pivotally connected to a wrist watch at their inner ends, the free end of one of the members being provided with a plurality of spaced perforations, a split lug mounted on the free end of the other member, the free end of the said second member being provided with a slotted portion in alignment with the space between the split portion of said lug whereby the split portions of the lug will be located in expanded relation with each other, said split portions of the lug adapted to be contracted and forced through one of the perforations in the free end of the first member with the split portions of the lug expanding within the perforations and locking the free ends of the two members together, and a keeper slidably mounted on the second member and provided with a tongue projecting forwardly from the lower face of the keeper and adapted to engage the under side of the free end of the first member when said keeper is locked on the lug of the second member and when the free ends of said members are located in face to face engagement with the split lug received in one of the plurality of perforations in the free end of the first member.

5. A band for securing wrist watches comprising a pair of members adapted to be pivotally connected to a wrist watch at their inner ends, the end of one of said members being provided with a plurality of perforations, the free end of the other member being provided with a split lug adapted to be received by one of the perforations and the free end of the first member, and a keeper slidably mounted on one of the members and provided with a perforation adapted to receive the split lug when said lug has been received within one of the perforations in the free end of the first member.

6. A band for securing a wrist watch in

position on the wrist of a person comprising two members adapted to be pivotally mounted at their inner ends on a wrist watch, one of the members being provided
5 with a plurality of perforations adjacent its free end, a lug mounted on the free end of the second member, a keeper slidably mounted on the second member and provided with a tongue having a perforation adjacent its
10 outer end, said lug on the free end of the second member adapted to be received by one of the perforations in the free end of the first member, the perforation in the tongue of the keeper adapted to receive the lug on the second member for maintaining 15 the free end of the first member locked in position between the free end of the second member and the tongue of the keeper.

HERBERT KEMP SMITH.
